US00D413803S

United States Patent [19]

Albright et al.

[11] Patent Number: Des. 413,803

[45] Date of Patent: ** Sep. 14, 1999

[54] BATTERY PACKAGE

[75] Inventors: **Gerald A. Albright**, Middleton; **Robert C. Gaffney**, Sun Prairie; **Richard L. Pedracine**, Madison; **Ross Mack**, Dane; **Ron Hellenbrand**, Middleton, all of Wis.

[73] Assignee: **Rayovac Corporaion**, Madison, Wis.

[**] Term: 14 Years

[21] Appl. No.: 29/094,324

[22] Filed: Sep. 30, 1998

[51] LOC (6) Cl. 09-07

[52] U.S. Cl. D9/423; D9/425

[58] Field of Search D9/420-425, 428, D9/432, 414, 337; 206/327, 703, 704, 705, 461-471, 508; 220/334, 337, 669-675; 229/406

CLAIM

The ornamental design for a battery package, as shown and described.

DESCRIPTION

FIG. 1 is a perspective view of a battery package showing our new design; shown in an open position;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view; and

FIG. 6 is a bottom plan view.

FIG. 7 is a perspective view of a second embodiment of a battery package; shown in an open position;

FIG. 8 is a front elevational view thereof;

FIG. 9 is a rear elevational view thereof;

FIG. 10 is a right side elevational view thereof, the left side elevational view being a mirror image thereof;

FIG. 11 is a top plan view; and

FIG. 12 is a bottom plan view.

FIG. 13 is a perspective view of a third embodiment of a battery package; shown in an open position;

FIG. 14 is a front elevational view thereof;

FIG. 15 is a rear elevational view thereof;

FIG. 16 is a right side elevational view thereof, the left side elevational view being a mirror image thereof;

FIG. 17 is a top plan view; and,

FIG. 18 is a bottom plan view.

The broken lines showing of the batteries is for illustrative purpose only and forms no part the claimed design.
